UNITED STATES PATENT OFFICE.

ELOF NORDSTROM, OF EAST ORANGE, NEW JERSEY, ASSIGNOR TO AMERICAN DAN BOTTLE SEAL CORPORATION, OF DOVER, DELAWARE, A CORPORATION OF DELAWARE.

SORTING MACHINE.

Application filed April 24, 1922. Serial No. 556,146.

To all whom it may concern:

Be it known that I, ELOF NORDSTROM, a citizen of the United States, and a resident of East Orange, county of Essex, State of New Jersey, have invented certain new and useful Improvements in Sorting Machines, of which the following is a specification.

This invention relates to a machine for sorting cork inserts that are used in metallic bottle caps. These cork inserts, as they come from the manufacturer, are not always of uniform shape and thickness, and the object of the present invention is to construct a machine which will sort out and reject those which are not of normal shape. I find that the rejects may be classified as follows:—

- a. Those which are too thin.
- b. Those which are too thick.
- c. Those which are wedge-shaped.

The problem, therefore, was to construct a machine which would select these three classes of unsatisfactory inserts, and separate them from those of normal size.

In the accompanying drawings:

Figure 1 represents in side elevation and partial section a view of the complete apparatus.

Figure 2 is a detail of the supporting mechanism.

Figure 3 is a detail of the selecting cylinder.

Figure 4 is an end view of the selecting cylinder.

Figure 5 is a longitudinal section of the selecting cylinder.

Figure 6 is a detailed view of the rotating evener.

Referring now to Figure 1, the cork inserts are introduced into the hopper 1, which has a traveling apron or belt 2 adjacent or lying on its inclined lower side 3, whereby the cork inserts 4 are carried up out of the hopper. The belt is carried and propelled by suitable pulleys 5. A rotating arm 6, mounted on a shaft 7, and driven in a direction contrary to that of the belt, operates to remove and throw back into the hopper any inserts that are not lying flat on the belt. By this means, a single layer, and a single layer only, is carried up by the belt and over the pulley 5, and slid down on the incline 8. When they leave this incline, they drop into the upper end of the sorting

cylinder 9, as shown more particularly in Figure 5. This cylinder is mounted on an incline, as shown in Figure 1, so that the cork inserts will gradually drift down as the cylinder is rotated, and in tumbling over, will be presented consecutively to the various selective mechanisms. The first half of the cylinder is devoted to eliminating the thin rejects, and for this purpose plates 10 are provided. These plates make up the perimetral walls of the cylinder, and are arranged to overlap each other, but are held apart at their overlapping edges by adjusting screws 11. Said plates are thus adapted to form longitudinal openings of uniform width thruout the length of said plates. For this purpose, the free edge of each of said plates 10 is angularly bent to lie parallel to the adjacent plate which it overlaps. In the first half of the cylinder, the space thus adjusted between the overlapping edges of the plates is so set as to allow any cork insert to pass through and drop upon the floor, if it is not of sufficient thickness. In the second half of the cylinder, this adjustment is such that only those inserts which are not too thick will pass through the openings and fall into space 12, in which they are caught by the cylinder casing 13, and from which they may be removed in any suitable way. In the meantime, the thick rejects continue in the cylinder and are finally dumped into chute 14.

The third class of rejects, namely those which are wedge-shaped, will stick in the space between the plate edges and be carried up to the top where they will be dumped into a trough 15 that will carry them out of the cylinder. This dumping action will now be described.

The plates are made slightly resilient, and are fixed at points 16 to the cylinder end frame 17. Their free angularly bent edges are provided with a reinforcing strip 18, which rests against the ends of the adjusting screws 11. A rock shaft 19, pivoted in the end frames of the cylinder, carries an adjustable screw tappet 20 and a tipping arm 21. A stationary block 22, fastened to the frame 23 of the machine, is so set as to tip this arm when the plates arrive at a point just beyond the top of its circular path and by turning the rock shaft, causes the screw tappet to spring back the plate and

thus allow any inserts that are caught thereby to drop into trough 15, by which they are carried out of the cylinder. The trough 15 may be covered at the lower end 30 so as to prevent the accidental dropping therein of the standard inserts that may be tumbled on to it. The end frames of the cylinder are mounted between rolls 24 which serve as supports and guides for the same. These 10 rolls 24 are carried on axes 25, mounted in the stationary frame 26. The cylinder may be operated in any suitable manner, and I have shown a grooved pulley 27, driven by a belt 28 as a preferred means of operation. 15 At 29, in Figure 4, is shown a box for catching the thin rejects.

I claim:—

1. A sorting machine comprising a rotatable cylinder of overlapping plates, one edge 20 of each of the plates capable of movement away from the stationary edge of the next plate and means for automatically tipping the plates in succession as they reach their upper position.

2. A sorting machine comprising a cylinder 25 with a series of overlapping plates, each plate being of resilient material, fastened rigidly at one edge and overlapping on the inside of the rigid edge of the adjacent plate, and automatic means for springing 30 these plates when they reach the upper part of their revolution to open the gap and drop any object caught therein.

3. A sorting machine comprising a rotatable cylinder, the cylindrical wall of which 35 is composed of a number of longitudinal plates movable respectively about their lateral edges and means for automatically separating the plates by a uniform distance throughout their length. 40

4. A sorting machine comprising a rotatable cylinder, the cylindrical wall of which is made of a number of longitudinal overlapping plates and means for automatically tipping the plates throughout their length so as 45 to make an opening between them of uniform width. 40

ELOF NORDSTROM.
